ABSTRACT

The hooded piece of clothing enables the user to quickly convert the hood into a facial covering, by using an opening in the fabric, which can be quickly opened or closed by a fastener. The drawstrings on either side are pulled down to tighten the facial covering around the face.

HOODIE MASK

**CROSS REFERENCE TO RELATED
APPLICATIONS**

This application claims priority of and incorporates by reference U.S. provisional patent application No. 63/015, 511, filed on Apr. 25, 2020.

BACKGROUND OF THE INVENTION

Facial coverings are known to prevent the transmission of airborne diseases, by preventing expelled infectious particles from coming into contact with other, non-infected individuals. Situations where facial coverings are required in public spaces, but not in private spaces are now common due to the ongoing COVID-19 pandemic, and as such, ensuring that one has a facial covering available to use at all times is important. Hooded clothes are commonly worn, and other hooded clothes are available with sewn-in or otherwise attached facial coverings. However, these facial coverings are often unable to be detached, removed, or stored in such a way that makes the mask easy to store away when not in use also readily available to be worn again.

BRIEF SUMMARY OF INVENTION

A hooded sweatshirt (101) with an integrated face mask (102) in the hood of the sweatshirt (103), which can be opened and closed, and which can be tightened around the face with drawstrings. (104)

BRIEF DESCRIPTION OF VIEWS

FIG. 1. depicts the closed position of the mask at the top 35 of the hooded portion of the sweatshirt

FIG. 2. depicts the side view of the close opening on the top of the hood

FIG. 3. depicts the converting the hood into a mask by 40 opening the closed portion of the hood, pulling the facial covering portion of the hood down around the nose and mouth, and adjusting the mask by pulling downwards on the drawstrings, such that the mask tightens around the face.

DETAILED DESCRIPTION OF INVENTION

A hooded piece of clothing (101) is comprised of clothing to be worn on the body, with a flap of fabric, the hood, (103) attached to the back portion of the neck opening which can be used to cover the head. The hoodie mask is a hooded piece of clothing where the hood section can be partially split, such that there is a hole in the hood. (105). The hole is original secured with a zipper, hook and loop fastener, buttons or some other fastener. (201) When the hole is open, if the hood is worn on the head, the face mask portion of the hood is comprised of the material at the front-most part of the hood, (102) (202) which can be pulled downwards in front of the face to cover the nose and mouth. The mask is then tightened around the nose and mouth with two drawstrings located near the chest and neck of the wearer (104).

2

The mask is tightened by pulling downwards on the drawstrings, which bunch the material on the outside edge of the hood, (203) including the edges of the face mask. The bottom edge of the hole (301) that was originally closed by 5 the fastener is now located above the nose of the wearer, but below the eyes, and the top edge of the hole (302) is now located above the eyes of the wearer, such that the wearer is able to see through the hole. The mask can be loosened by loosening the material on the outer edge of the hood, (303) the hole can be re-fastened so that the hole is closed, and the 10 hood can be worn as any other hooded piece of clothing. As seen in FIG. 2, the hole (105, 201) is closer to the front of the hood than to the back of the hood. The front of the hood is the portion of the hood that defines the face opening. The back of the hood is the portion of the hood that attaches to the rest of the hooded piece of clothing.

The invention claimed is:

1. A hooded piece of clothing comprising a hood and a body attached to the hood at a back edge of the hood, said hood comprised of a top portion comprised of an edge line 20 that defines a face opening of the hood, said hooded piece of clothing comprising:

a hole opening in the top portion of the hood, where the hole opening is substantially horizontal in relation to the edge line of the top portion of the hood, said hole opening having a top edge and a bottom edge, said top and bottom edge in a first closed state fixed together by a fastener, and in a second open state, said top and bottom edge being unfixed, thereby permitting the top edge and bottom edge to separate and form the hole opening in the second open state;

a fabric region of the hood that is between the lower edge of the hole opening and the edge line of the top portion of the hood;

at least one drawstring attached to the fabric region of the hood, said at least one drawstring configured such that when said at least one drawstring is pulled when the fastener is in the second open state, the fabric region of the hood is repositioned to cover a nose and a mouth of a wearer of the hooded piece of clothing, while simultaneously leaving eyes of the wearer exposed through the hole opening; and

said fastener further configured so that when the fastener is fixed together, the hole opening returns to the first closed state,

where a distance from a center line defined by where the top edge of the hole opening and the bottom edge of the hole opening meet via the fastener in the closed state to the edge line of the top portion of the hood is between 5 inches and 6 inches, and

where the hole opening is closer to the edge line in the top portion of the hood than to where the hood is attached to the body at the back edge of the hood.

2. The hooded piece of clothing of claim 1 where said hole opening is about 9 inches long.

3. The hooded piece of clothing of claim 1 where the fastener is a zipper.

4. The hooded piece of clothing of claim 1 where the fastener is a hook and loop fastener.
